UNITED STATES PATENT OFFICE

JOHN W. BUSSEL, OF COLUMBIA, PENNSYLVANIA

SINK, TRAY, AND TABLE COMBINATION

Application filed June 24, 1932. Serial No. 619,139.

This invention relates to an improved sink, tray and table combination, the object being to provide an improved structure wherein the advantages both of a sink with one or 5 more drain boards and a tub are provided.

Another object of the invention is to provide a combined sink and tray structure of one integral piece with a tub formation extending an appreciable distance below the 10 drain board or boards and projecting a short distance thereabove so that liquid will not discharge into the tub.

An additional object, more specifically, is to provide a combined drain board, sink and 15 tub structure wherein the tub structure projects above the sink structure, and also, wherein there is a separate drain for the sink structure and the tub structure.

In the accompanying drawing,—

20 Figure 1 is a perspective view of a sink and tray combination disclosing an embodiment of the invention.

Figure 2 is a top plan view of the structure shown in Figure 1.

25 Figure 3 is a sectional view through Figure 2 approximately on line 3—3, the same being on an enlarged scale.

Referring to the accompanying drawing by numerals, 1 indicates what may be termed 30 a tub, 2 what may be termed a sink, and 3 and 3' what may be termed trays or drain boards. While two drain boards have been shown in the drawing, it will be understood that one drain board could be used if desired without departing from the invention.

All of these members are preferably cast in 35 one solid piece and then covered with enamel.

In forming the depressed portion or sink 40 2, the same is depressed below the drain boards 3 and 3', and also inclined slightly from the front to the rear, as indicated in Figure 3. At the rear there is a depressed cavity or compartment 4 having a bottom, and through this bottom extends a drain pipe 45 5. The drain pipe 5 is connected also to a drain pipe 6 connected to the bottom of the tub 1 so that both drain pipes may discharge out of the same discharge pipe 7, which pipe is connected in any desired manner with any 50 kind of a trap.

In forming the device there is provided an apron 8 which merges into the end walls 9 and 10, and said end walls in turn merge into a back wall 11. As illustrated in Figures 1 and 3 the tub 1 is integral with the other 55 parts of the device, but is provided with an upwardly extending portion or wall 12 projecting a desired distance above the bottom of the sink 2. By reason of this construction if any water or other liquid is poured into 60 the sink 2, it will not enter the tub 1, and also, if water or other liquid should be poured on to either of the drain boards, none of the water will enter the tub 1, but will pass on to the sink 2 and from thence around to the 65 depression or cavity 4, and finally out through the pipe 5.

Coacting with the tub 1 is a dishpan 13 having a flange 14 fitting over the top of the wall 12, as illustrated particularly in Figure 3. 70 When washing anything in the dishpan 13, if some of the water is spilled out it will find its way to the drain pipe 5 and will not enter the tub 1. Whenever desired, the front edge of the pan 13 could be grasped by the fingers 75 and the pan tilted so as to pour the water directly into the depression 4, thus preventing any of the liquid from entering the tub 1. In this way the tub 1 is maintained clean 80 at all times so that it may be used for washing clothes or any other article at any time without especially cleaning. Normally, the dishpan 13 is left in place whether it is used or not. When mounted as shown in Figure 85 3, it acts as a cover for the tub 1. Under some circumstances, it may be desirable to have a flat plate 15 placed across the tub 1 and the dishpan 13. This plate may be of any desired material, as, for instance, steel covered 90 with enamel and provided with any desired number of legs 16, each leg having the lower end covered by a cushion, as, for instance, a rubber socket 17. These legs support the plate 15 a very short distance above the dishpan 13 so that any weight placed on this 95 plate will not be communicated to the dishpan. Also, the edges of the plate 15 are preferably turned over, as indicated at 18, whereby if any liquid should be spilled thereon, it will flow into the sink 2. This board 100

is intended for many uses, as, for instance, to support an ironing board when a small amount of ironing is desired, or to support sauce pans, or other articles when preparing 5 a meal.

I claim:—

1. A combination structure of the character described including a body formed as a pair of drain boards merging into a centrally de-10 pressed sink portion positioned between the drain boards, a tub extending through the sink portion with most of the tub below the sink portion and a comparatively low wall extending above the sink portion so that 15 liquid from the sink portion will not drain into the tub, means forming an outlet at the bottom of the tub and means at the rear of said low wall forming an outlet to said sink portion.
- 20 2. A device of the character described including a body having a back, a substantially flat sink inclined slightly toward said back, means forming a drain near said back, a tub projecting through said sink and having an upstanding wall projecting above said drain 25 and sink, and means at the bottom of said tub forming a drain for said tub.

3. A device of the character described including a body formed with a substantially flat portion acting as a sink having upstanding walls, two of the walls merging into drain boards connected to the opposite ends of said sink, one of the walls merging into a front protecting wall structure, and the other 30 merging into a back protecting wall structure, a tub integral with the sink and having an upstanding wall projecting above the sink, a drain pipe connected to the sink at the rear of the tub and below the upper edge 35 thereof, and a separate drain pipe connected to the bottom of the tub.

4. A device of the character described comprising a body including a pair of spaced drain boards merging into a centrally positioned comparatively flat section depressed below the drain boards and acting as a sink, said sink being inclined toward the rear and at the rear having a depressed socket merging into a drain outlet and a tub carried by 45 said sink, the upper edge projecting above the bottom of said sink whereby liquid deposited on the drain boards or sink will pass around to the rear of the tub into said socket, and means forming a drain from the bottom 50 of said tub.

5. A device of the character described including a tub having a drain at the bottom, said tub at the upper end being turned over and formed with a radiating flange providing 60 a surrounding depressed portion acting as a sink, said depressed portion at the rear of the tub being formed with a socket whereby anything poured into the depressed portion will enter said socket, said socket having an 65 outlet opening.

6. A device of the character described including a tub having a drain at the bottom, a dishpan open only at the top having a curved upper edge fitting over the upper end of the tub and acting as a cover therefor, means connected with the tub below the upper edge and above the bottom thereof forming a sink, said means having an apertured socket at the rear of the tub, whereby when said dishpan is swung toward the rear of the sink it will discharge into said socket and said tub will remain clean. 70

7. A device of the character described including a tub and drain at the bottom, means connected to and surrounding the tub a short 75 distance below the upper end of the tub for forming a sink, means forming a drain for said sink, a dishpan open only at the top with a rolled upper edge fitting over the upper edge of said tub and acting as a lid 80 therefor, and a plate provided with a plurality of legs resting on said sink and acting as a table, said plate covering said dishpan and most of said sink. 85

8. A device of the character described including an integral structure formed with a sink section merging at its sides into oppositely extending drain boards discharging into the sink section, a back member merging into said sink at the rear thereof and into the drain boards at their rear edges, a pair of substantially triangular shaped side members merging into the ends of said back and respective drain boards, and a tub merging at its upper end into a sink section, said tub 90 projecting above said sink section to prevent liquid from flowing from the sink section into the tub, and means forming a drain from the said sink section. 95

9. A device of the character described comprising an integral structure formed with a central portion acting as a sink, said central portion being inclined and formed at the lowermost point of the surface with an integral depression having a discharge opening 100 in the bottom, said central section having upstanding walls at two of its edges, said walls merging into the sink section at their lower portions and at their upper portions merging into oppositely extending drain boards, 105 and a tub integral with the sink arranged substantially centrally thereof with a portion thereof projecting above the sink so that liquid in the sink will drain into said depression and not into said tub whereby the 110 tub will remain clean while the sink and drain boards are in use. 115
